(57) **CLAIM**

The ornamental design for a garden bench, as shown and described.

DESCRIPTION

FIG. 1 is a front perspective view of a garden bench showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a rear perspective view thereof;

FIG. 9 is a front perspective view of an embodiment of the garden bench of my new design having a woodgrain pattern on the surface thereof.

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a rear perspective view thereof.

The broken lines shown in FIGS. 7 and 15 illustrate portions of the garden bench that form no part of the claimed design.

1 Claim, 8 Drawing Sheets
